UNITED STATES PATENT OFFICE.

JAMES M. EDER, OF NEW YORK, N. Y.

SMOKING IMPLEMENT.

980,080.

Specification of Letters Patent. Patented Dec. 27, 1910.

Application filed March 10, 1910. Serial No. 548,399.

To all whom it may concern:

Be it known that I, JAMES M. EDER, a citizen of the United States, and a resident of the city of New York, borough of Manhattan, in the county and State of New York, have invented a new and Improved Smoking Implement, of which the following is a full, clear, and exact description.

This invention relates to smoking implements, such as pipes, and cigar or cigarette holders, and has reference more particularly to a device of this class, comprising a tobacco-holding member, a stem having a mouth-piece and provided with a passage of substantially uniform diameter, extending from the tobacco-holding member to the mouth-piece, and an absorbent cartridge in the passage.

An object of the invention is to provide a simple, inexpensive, and durable smoking implement of the class described, which can be fashioned in different forms, and from different materials, which is sanitary when in use, which obviates certain of the objectionable features commonly attending the use of tobacco, which provides an absorbent cartridge for freeing the smoke, before it enters the mouth of the smoker, from nicotine and other unpleasant and deleterious impurities, which is so constructed that the cartridge can be removed without touching it with the hand, and which obviates the necessity of cleaning the smoke passage from the tobacco-holding member to the mouth-piece.

A further object of the invention is to provide a smoking implement in which the passage between the tobacco-holding member and the mouth-piece can be easily cleaned, by simply removing the absorbent cartridge, which is so constructed that the used cartridge can be removed by merely inserting a new cartridge and forcing it through the smoke passage, and which is operable to remove the butt of a cigar or cigarette from the tobacco-holding member without touching the butt with the fingers.

The invention consists in the construction and combination of parts to be more fully described hereinafter and particularly set forth in the claims.

Reference is to be had to the accompanying drawings forming part of this specification, in which similar characters of reference indicate corresponding parts in all the views, and in which—

Figure 1 is a longitudinal section of a

tobacco pipe comprising an embodiment of my invention; Fig. 2 is a perspective view of the mouth-piece of the pipe, showing the same removed from the stem; Fig. 3 is a perspective view of a cartridge used in connection with my invention; Fig. 4 is a longitudinal section of a cigar holder constituting a modified form of my invention; Fig. 5 is a view similar to Fig. 4, showing certain of the parts in different position and illustrating the manner of operating the holder, to eject the butt of a cigar; and Fig. 6 is a longitudinal section of a cigar-holder comprising a further modified form of my invention.

Before proceeding to a more detailed explanation of my invention, it should be clearly understood that the absorbent cartridge may be fashioned from any suitable material adapted for the purpose, for example, it may consist of a cylindrical roll of absorbent paper which has a longitudinal bore through which the smoke flows, and into the pores of which, moisture in the smoke, and the other impurities, enter. The passage between the tobacco-holding member and the mouth-piece is of substantially uniform diameter, and the cartridge is correspondingly formed to fit snugly therein, and extends from the end of the mouth-piece to the entrance of the tobacco-holding member, completely filling the smoke passage. Hence, if the cartridge has become foul it can be ejected from the smoke passage by merely forcing into the same a new cartridge. This obviates the necessity of cleaning the smoke passage in any way other than by the removal of the cartridge itself.

Certain of the details of construction form no part of the invention and can be varied in accordance with individual preference and special conditions, without departing from the underlying spirit of the invention.

Referring more particularly to the drawings, I have shown in Fig. 1 a pipe comprising a tobacco-holding member or bowl 10 having associated therewith a stem 11 fashioned from wood or any other suitable material. The stem has a bore 12 therethrough which communicates interiorly with the bowl. At the end remote from the bowl, the bore is enlarged to form a socket 13 which receives a correspondingly formed extension 15 of the mouth-piece 14. The latter may be of any suitable shape, and is fashioned from hard rubber, amber or other

material. A metal or other band 16 encompasses the end of the stem, adjacent to the mouth-piece, in the usual manner. The mouth-piece has a bore 17 therethrough, 5 which at the end adjacent to the stem has a threaded enlargement 18. This receives the correspondingly threaded end of a tubular member 19 fashioned from metal or any other suitable material. The arrangement 10 is such that the internal diameter of the tubular member 19 is substantially equal to the diameter of the bore 17. The member 19 is of such length that when the mouth-piece is in position, the member 19 extends 15 to the entrance of the bowl, as is shown in Fig. 1. In this way I provide a smoke passage from the bowl to the end of the mouth-piece, which is substantially uniform in diameter, and which is smooth and free from 20 obstructions. The cartridge 20, which I employ is of cylindrical form and has a longitudinal bore or passage 21 therethrough. It fits snugly within the bore 17 of the mouth-piece, and within the tubular member 19, 25 extending from the end of the mouth-piece to the entrance of the bowl. When the mouth-piece is removed, the cylindrical member 19 and the cartridge are drawn from the stem of the pipe, with the mouth-piece. As previously explained, the removal 30 of a fouled cartridge, by replacing it with a new one effects the cleaning of the smoke passage.

In the form of my invention shown in 35 Figs. 4 and 5, I provide a tobacco-holding member 21 which is formed to receive the end of a cigar, and thus act as a cigar-holder. The mouth-piece has a bore 23 therethrough, provided with a threaded enlargement 24. 40 This receives the correspondingly threaded end of a tubular member 25; the internal diameter of which corresponds to the diameter of the bore 23. The cartridge 26 is located in the smoke passage formed by the 45 bore 23 and the tubular member 25. An annular member or band 27 is secured upon the tobacco-holding member 21, so that the mouth-piece can move freely toward and away from the tobacco-holding member. 50 The latter has a threaded bore 28 in which is mounted a correspondingly threaded sleeve 29, which sleeve receives the end of the tubular member 25. The extremity 30 of the tubular member 25 is outwardly disposed to 55 limit the movement of the tubular member within the sleeve and to prevent the mouth-piece from being drawn out of the band 27. A spring 31 is arranged upon the tubular member 25 and engages the adjacent ends of 60 the tobacco-holding member and the mouth-piece, tending to separate them, as shown in Fig. 4. By forcing the mouth-piece inward against the tension of the spring, toward the tobacco-holding member, the end 30 of the 65 tubular member is moved into the recess or

bowl of the tobacco-holding member, and then serves to eject therefrom the butt of a cigar 32, as is shown in Fig. 5. It will be understood that while the band 27 is shown secured to the tobacco-holding member, it 70 can just as well be fastened upon the mouth-piece, and be movable with respect to the tobacco-holding member, if the parts are not tapered.

In the modified form of the device, shown 75 in Fig. 6, I dispense with the spring 31. In this case the frictional engagement of the parts serves to hold them in the relative positions shown, in which the holder is extended so that the tubular member is retracted, and does not project into the tobacco-holding member. The modified form includes a cartridge 26^a, which has an elongated body of substantially uniform diameter, and is provided at one end with an outwardly extended, tapered or funnel-shaped part 26^b. This is located within the tobacco-holding member 21 and seats at the inner 80 end thereof. It is formed to receive the extremity of the cigar, so that it is practically impossible for smoke to escape at the end of the cigar, without passing directly through the cartridge. In this way, all contamination of the tobacco-holding member is obviated, and the device is rendered more sanitary, and cleaner. 90

Having thus described my invention, I claim as new, and desire to secure by Letters Patent:

1. A device of the class described, comprising a tobacco-holding member, a mouth-piece, a tubular member associated with said mouth-piece, a threaded sleeve in said tobacco-holding member, and movably receiving said tubular member, said tubular member having at the end a stop to limit the movement thereof with respect to said sleeve, a collar encompassing said tobacco-holding member and said mouth-piece, and an absorbent cartridge in said mouth-piece and said tubular member.

2. In a device of the class described, a cartridge fashioned from absorbent material, and having a laterally extended part adapted to receive directly the end of a 1 cigar.

3. In a device of the class described, an absorbent cartridge having a tubular body, and at one end an outwardly tapered extension adapted to be received within the tobacco-holding member, and formed to receive directly, the end of a cigar.

In testimony whereof I have signed my name to this specification in the presence of two subscribing witnesses.

JAMES M. EDER.
